Charles J. Shepard   New York.
 Letters Patent (Design No. 145) Dated 28th August 1847

The schedule referred to in these Letters Patent and making part of the same.

To all to whom these presents may come, Know Ye... That I, Charles J. Shepard, of the City and County of New York, Stone Manufacturer, Have invented or produced, and made and applied to use, a certain new and original two part design, of Figures and Letters, to be cast in metal, which design is adapted for the fronts or fronts and ends of Stones; such design being intended by me, for use with a new and improved looking stone, for which I am also seeking Letters Patent of the United States; but I do not hereby intend to limit said Design to such use, as the ornamental portions thereof are of a general character, which renders such parts available for use in other articles, and for which ornamental portions of said design I seek Letters Patent of the United States: And that the said design is, artistically, fully and substantially set forth and shown in the following description, and in the drawing annexed to, and making a part of this my specification thereof: wherein the Fig. 1 represents the front plate of a stone, and Fig. 2, one end plate, the opposite extremities and the back, or inside part, which end plate is accurately fitted, to match and connect, at the angles, with the back plate, or front plate of the stone, so that each end plate is the exact counter part of the other: The Fig. 3 is a section of Fig. 1; and Fig. 4 is a section of Fig. 2 showing the constructive form of the plates, as they receive the ornaments, and are at the same time, made useful in fitting the stone together. The letters and numbers used, as marks of reference apply to the like parts, in each of the Figs, except when otherwise stated.

Fig. 1 is the front plate, with α the oven door, and β the fire door, with hinges and latches as usual; ϵ is the fascia forming a projecting front tablet, furnished with a small ornical and rather flat reading.

to fill the blank spaces at each end and having the words "Shepards Patent", cast on the fascia, in medium relief, in letters, made by small single volute formed figures, set in counter position to each other, in the manner shown in nearly full size, in the detached Fig. 7. Towards each end of the fascia c is an ornament, commencing with a double volute formed figure, the same as those shown in Fig. 6, but with a dot above and below the vertical centre, and flanked by one vertical and two horizontal ellipses, and a short baton, with a back head, as shown in nearly full size in Fig. 9. Within, and all around the edges, the fascia c has an ornament, formed of double volute formed figures, in close contact, the same as those shown in Fig. 6, and without any dots above or below them; these, at each angle are either cros mitred, or have rosettes, as shown in Fig. 1. and around and just within the edges, the flat surface below is ornamented with the like double volutes as shown in Fig. 6 either cros mitred or with rosettes at the angles. The fire door d is formed as a flat dish, projecting outwards, the inner and plain flat of the edge fitting against the face of the plate a, and the outer flat of the edge ornamented all round, with the same double volute figures, before referred to, as shown in Fig. 6: within these the edges of the dish part are formed in a regular series of semiscallops all around: within the edge of the flat surface, a belt of the double volutes, as in Fig. 6 circumscribes a border, within which is a wreath, having a stalk with leaves, and a cup flower, forming a running fancy figure, successively, as shown in two portions, in nearly full size, in the detached Fig. 5. cast in medium relief, on the surface of the metal. Within this, is a border formed of the same double volutes as shown in Fig. 6 and cros mitred or rosetted, at the angles, to enclose an oblong square panel, on the centre of which is the letter S, formed by the single volute shaped and counter positioned figures, shown in the detached Fig. 7. On the face of the plate a, a corresponding wreath to that before described, ascending on each side of the fire door turns inwards so that it meets and finishes over the centre of the fire door ^{door}, with one length turned off.

toward the oven door c; the oven door c is made and ornamented, so that it is exactly similar to the fire door, all round the edges, but as the size of surface is increased, and the longest dimension horizontal, the central panel is largest that way, and is marked with the words "Stove Range" cast in medium relief, and each letter made, by the small single volute formed and counterpositioned figures shown in Fig. 7. In the centre of the panel is a double volute, similar to those shown in Fig. 6, with a dot above and below the vertical centre, and having one vertical and three horizontal ellipses, on each side of it, and a short baton, with a ball head, at each extremity, as shown in nearly full size, in the detached Fig. 8. Below, between and above the hinges of the oven door, the same figure of wreath is cast on, that is before described and referred to, as shown full size in Fig. 5, and the last length is curved slightly toward and over that corner of the oven door, to correspond with the opposite one over the latch.

In fig 2. b, is the end plate, before referred to, with a fascia having a projecting tablet g, ornamented with a border of the double volute formed figures, shown in Fig. 6, this border is shown, as circumscribing a block letter inscription, referring to a stove, for which I am seeking separate Letters Patent; but any inscriptive reference may be used, on this part; below this fascia g, are two mock doors f that form two projecting or raised panels, each having an external border, of the double volute formed figures, shown in Fig. 6, cross mitred, or rosetted, at the angles, and circumscribing a wreath, similar to that shown in Fig. 5. Within this wreath, is an inner border formed by the double volutes, shown in Fig. 6, and rosetted, or cross mitred at the angles, to inclose a space within which is the letter S formed of the single volute shaped figures, shown in fig. 7. Near the lower and two side edges, the plate b, has a border of the double volutes, shown in Fig. 6, either cross mitred or rosetted at the angles. Within this, a wreath, as shown in Fig. 5, commences near the lower centre, and trailing each way, passes up, to near the top of the plate, between the outer edge of the plate, and the ends of the mock doors, and of the fascia: Next beneath the mock doors, the wreath commencing in the centre proceeds up, in the hollow space between the two

mock doors, and trails each way beneath the mock doors, to join the vertical wreaths, near the edges of the plate: Within the two vertical and horizontal lines of wreath, thus formed, a border of the double volutes shown in Fig. 6 incloses a panel, on which are the words "The Gem", the letters of which are formed, by a series of the single and counterpositioned volutes, shown in Fig. 7, the two words are divided, and flanked by a line of three horizontal ellipses, on the panel: All the ornamental figures above described and referred to are cast in medium relief, on and with the metal plate itself, and are equally prominent therewith: A small head seen best, in the lower part of the decorative Fig. 8, surrounds all the more ornamental portions, as it lies between them and the extreme edge.

It is difficult to find, or make terms of art, that shall be radically applicable to new and fancy figures, or shapes, in new designs: therefore the common terms in use, that come nearest the given subject, have been herein used, conjointly with a direct reference to the given subject, itself, represented in a nearly full sized detached Fig. so that the identity of the parts referred to, is readily distinguished.

Having described my improved design for stove fronts, or stovefronts and ends, I do not herein claim the mode of making the front or end plates, or of making or fitting the doors, or of fitting the front and end plates together, as whatever of legal claim I may have, on these points, is embodied in a separate application for a Patent on construction.

But I do claim as new, and of my own invention or production, the forming and placing the single volute shaped figures, in counterposition with each other, as seen best in the detached Fig. 7, and using them when so formed and placed, to produce letters and words, or to form borders or figures of any character in the manner described and shown.

I claim the peculiar form of this double volute shaped figures, shown in Fig. 6, and the placing such figures as borders, and using them separately, in other parts of ornamental designs, as central or flanked ornaments, alone, or separate, or conjointly with other parts, either similar, or different to, those shown in the detached Figs. 8 and 9, and as applied on this design, in the

Des. 145

5

Manner described and shown.

I claim the peculiar form of the wreath shown in the detached
Fig. 5, and as applied in the parts of this design, when used for ornamental
purposes, of this, or any similar kind, either alone, or in conjunction with
the other parts, in the manner described and shown.

In witness whereof, I have hereunto set my hand, this thirtieth
day of June, one thousand eight hundred and forty seven.
